CATHODE RAY TUBE

Earl R. Woughter, Elmira Heights, and William J. Knochel, Elmira, N.Y., assignors to Westinghouse Electric Corporation, East Pittsburgh, Pa., a corporation of Pennsylvania

Application April 17, 1956, Serial No. 578,624

2 Claims. (Cl. 313—85)

This invention relates to cathode ray tubes and, more particularly, to electron beam shields for use in cathode ray tubes.

In cathode ray tubes, such as those used in television receivers, electrons emitted by electron beam generating means impinge upon a luminescent screen in such a manner as to excite the luminescent screen which emits light. More particularly, in a shadow mask color television tube as described in a copending application entitled "Color Television Tube" by William J. Knochel, Serial No. 564,720, filed February 10, 1956, now Patent 2,871,087 and assigned to the same assignee as the subject application, the luminescent screen is comprised of a plurality of groups of phosphor dots which emit different colors, e.g., red, green, and blue when they are excited by the impinging electrons. The electrons are emitted by an electron beam generating means, such as an electron gun or plurality of electron guns and are deflected by suitable deflecting means, e.g. magnetic fields supplied by coils external to the tube, in order to scan a suitable pattern. After the electrons are deflected, they travel in straight lines through a relatively field free region, pass through apertures in a shadow mask electrode and finally strike a phosphor dot which will emit the desired color. The apertures of the shadow mask electrode are in registration with the corresponding phosphor dot groups. To obtain pure saturated colors it is essential that an electron beam intended to excite, for example, red phosphor dots hit only these dots and that no other electrons arise within the tube which can strike and excite unwanted colors. The alignment and registration of the electron beam source, which is considered to include the deflecting means, the shadow mask apertures and the phosphor dots is, therefore, very critical and must be accurately done.

We have found that stray electrons may be generated within the cathode ray tube due to various causes. One cause of stray electrons is scattering when the primary electron beam hits the side walls of the envelope of the cathode ray tube at the extremities of the scanning pattern. Unless these scattered electrons are prevented from doing so, they may pass between the edge of the shadow mask electrode and the envelope wall and possibly after further scattering, collisions with the mask and the envelope wall, may excite the several phosphor colors of the luminescent screen more or less equally. This results in an array of the generally whitish illumination which strongly desaturates colors and degrades contrast. This effect is especially objectionable in the rounded corners of the so-called rectangular cathode ray tube envelope which is normally used in the television industry. The rectangular scanning pattern may cause many electrons to hit the wall particularly in the corner areas of the scanning pattern. It is not practical to make the shadow mask electrode large enough to touch the glass

2

envelope wall itself since the lateral positioning of the shadow mask electrode must be established by the various glass and metal positioning and locating means described in the above-mentioned copending Knochel application, 5 which lateral positioning is done independently of the location and shape of the shadow mask rim and cathode ray tube envelope wall.

It is accordingly an object of this invention to provide an improved cathode ray tube which produces a picture 10 with improved contrast.

It is another object to provide an improved color cathode ray tube which produces a picture with improved color resolution.

It is a further object to provide an electron beam 15 shield for a cathode ray tube.

It is still another object to provide an embossed electron beam shield for a cathode ray tube.

It is a still further object to provide an improved electron beam shield for a cathode ray tube which beam shield 20 is comprised of a metallic foil material.

These and other objects of our invention will be apparent from the following description taken in accordance with the accompanying drawing throughout which like characters indicate like parts, which drawing forms 25 a part of this application, and, in which:

Figure 1 is a perspective view, partly in section, of a cathode ray tube embodying our invention;

Fig. 2 is a plan view of the inside of the faceplate portion;

Fig. 3 is a sectional view of a detail portion of one embodiment of our invention;

Fig. 4 is a perspective view of a detail portion of another embodiment of our invention;

Fig. 5 is a sectional view of a detail portion of Fig. 4 35 as seen from the rear;

Fig. 6 is a detail view of a portion of Fig. 5, and

Fig. 7 is a plan view (of a detail portion) of another embodiment of our invention.

Referring in detail to Fig. 1, there is shown a cathode ray tube embodying our invention including an envelope member 11 which includes a face panel portion 13 and a funnel portion 19. The face panel portion 13 includes a faceplate portion 15 and a skirt portion 17. The funnel portion 19 includes a flared portion 21 and a neck portion 23. A luminescent screen 25 has been deposited upon the faceplate portion 15. Electron beam generating means 27 have been positioned in the neck portion 23 and generate electron beams 29, which, after traveling through shadow mask electrode apertures 33 of a shadow mask electrode 31, impinge on the luminescent screen 25 which is comprised of a number of phosphor dots 35. For simplicity, only one aperture 33 and a few dots 35 of the screen 25 are shown. A conductive coating 39 has been applied to the interior of the envelope member 11 and the face panel portion 13 has been sealed to the funnel portion 19 at a seal portion 41. An electron beam shield member 37, which will be more fully described below, has been inserted between the shadow mask electrode 31 and the electron beam generating means 27. This electron beam shield member 37 intercepts undesirable scattered electrons which may arise, for example, when electron beam 29 strikes the envelope wall and which would create undesirable edge effects, and impurity of color if they were allowed to strike the luminescent screen 25. This electron beam shield 37 also eliminates the possibility of an arc forming between the luminescent screen 25 and the seal portion 41 during the electric seal

process described in the Knochel application entitled "Color Television Tube" referred to previously.

Fig. 2 shows a plan view of the inside of the face panel portion 13 with the shadow mask electrode 31 in position and showing the skirt portion 17. The electron beam shield member 37 is positioned on top of the shadow mask electrode 31 as will be described below. Also shown are integral lock-in projection members 43 which will be more fully described below.

In Fig. 3 there is shown a side sectional view of a detail of a cathode ray tube showing how the electron beam shield member 37 may be positioned in one embodiment of our invention. The face panel portion 13 of the envelope 11 is shown including the skirt portion 17 and a part of the faceplate portion 15. The shadow mask electrode 31 rests upon a support land member 45. A fastening spring member 47 is inserted into a notch 59 in a lock-in projection member 43. The fastening spring member 47 is also attached to a hold-down ring member 49 to which is attached an electron beam shield positioning member 51 which holds the electron beam shield member 37 against the shadow mask electrode 31. A suitable material for the fastening spring member 47 is spring temper metal sold under the trademark "Inconel." The electron beam shield positioning member 51 may also be made of "Inconel" and may be of either wire or flat stock. If desired, the hold-down spring member 49 may be a wire to which an "Inconel" leaf spring electron beam shield positioning member 51 is welded.

The electron beam shield member may be made of aluminum having a thickness of ".010" to ".0015". This aluminum may be stamped from aluminum sheeting of desired thickness and after proper cleaning it may be inserted into the cathode ray tube. An aluminum electron beam shield member 37 will allow direct contact with the glass envelope member 11 thereby giving complete electron beam shielding because the electrons are not allowed to pass between the electron beam shield member 37 and the skirt portion of the envelope member 11. Also aluminum will not damage the glass during the heating cycles in the manufacture of cathode ray tubes, thus eliminating a source of possible breakage.

In Figs. 4, 5 and 6 there are shown portions of the part of the face panel portion 13 including the skirt portion 17 and the faceplate portion 15. The shadow mask electrode 31 is positioned upon a support land member 45 and the electron beam shield member 61 is held by a one piece electron beam shield positioning member 53. As can be seen, a portion of this electron beam shield positioning member 53 is inserted in the notch 59 of the lock-in projection member 43. Another portion of the electron beam shield positioning member holds the electron beam shield member 61 in touching relationship to the shadow mask electrode 31. We have found it desirable at times to emboss a portion 55 of the electron beam shield member 61 where the electron beam shield positioning member 53 holds the electron beam shield member 61 against the shadow mask 31. Therefore, it is seen that the electron beam shield member 61 touches the shadow mask 31 only at the embossed positions. This is advantageous because if the electron beam shield member 61 and shadow mask electrode 31 were required to be in touching relationship for large portions of their area, a perfect match would be required in order to prevent distortion of the shadow mask and the resultant color impurity. With small portions of the two members touching each other at the points where the shadow mask 31 rests on the support lands 45 or other mask support means, any slight deviation on the construction of the electron beam shield member 61 will not distort the shadow mask 31. The embossed portions 55 of the electron beam shield member 61 also provides an easy means of checking the seating of the electron beam shielding positioning member.

In Fig. 7 there is shown another embodiment of our

invention in which portions of electron beam shield members 57 are used rather than the electron beam shield member 37 or 61 shown in previous figures. The skirt portion 17 of the face panel portion 13, the shadow mask electrode 31 and the electron beam shield positioning members 53 are also shown. The partial electron beam shield member 57 as shown in Fig. 7, has in some instances, proven to provide sufficient electron beam shielding when located in the corner portions of the shadow mask electrode 31. This is primarily because the standard rectangular scanning pattern causes extensive bombardment of the tube walls at the rounded corners of the customary nominally rectangular glass tube envelope. It has also been found that the shadow mask electrode 31 may be positioned more closely to the glass envelope 11 in the flatter portions of the periphery of the shadow mask electrode 31 but it is difficult to make such a close fit in the corners of the shadow mask electrode 31.

We have also found that in some instances that it may be desirable to make the electron beam shield member 37 of thin aluminum foil such as that known as "Reynolds Wrap." We have found that if this thin aluminum foil is cut in strips having a width of approximately 6 inches and is folded twice leaving a strip $1\frac{1}{2}$ inches wide with the thickness 4 times the original foil, this latter strip may then be formed around a die to the desirable shape. After the shadow mask electrode 31 has been permanently inserted in the cathode ray tube the electron beam shield member 37 is then positioned next to the mask electrode 31 and is held by positioning means as described above or by any other means. After the electron beam shield member 37 is fastened in position, it may be placed against the glass envelope 11 thus filling the gap between the shadow mask electrode 31 and the skirt portion 17 of the face panel portion 13. Thus, this foil electron beam shield member 37 provides the necessary electron beam shielding as well as the arc protection of the luminescent screen 25. Also, the aluminum foil electron beam shield member 37 does not distort the shadow mask electrode 31 during heating cycles and does not scratch the glass panel. We have found that an electron beam shield member 37 made of aluminum foil holds its shape during the steps of preheating, electric sealing, annealing, exhaust and bake-out and while operating as a cathode ray tube. As can also be seen, it can be produced easily and cheaply.

Another advantage of using the fastening means described above is that the mask is allowed to "breathe" during the sealing and annealing cycles, therefore following more closely the direct contour changes of the glass panel.

While the present invention has been shown in a few forms only, it will be obvious to those skilled in the art that it is not so limited, but that it is susceptible of various changes and modifications both in structure and in materials without departing from the spirit and scope thereof.

We claim as our invention:

1. A cathode ray tube including an envelope member, said envelope member being comprised of a face-plate portion and a funnel portion, said funnel portion being comprised of a flared portion and a neck portion, an electron beam generating means positioned within the neck portion of said envelope member, a luminescent screen positioned adjacent said face plate portion, a shadow mask electrode having a plurality of apertures therein positioned between said luminescent screen and said electron beam generating means and a thin flexible metallic electron beam shield member positioned between said shadow mask electrode and said electron beam generating means and positioned adjacent said envelope member, said electron beam shield member being comprised of aluminum foil material.
2. In a cathode ray tube having an envelope member, a shadow mask electrode and a luminescent screen, an electron beam shield member comprising a thin, flexi-

ble annular metallic member having a peripheral configuration corresponding to that of said luminescent screen, said annular metallic member being comprised of a plurality of shaped layers of metallic foil material, said beam shield member being positioned adjacent said envelope member and said shadow mask electrode being positioned between said luminescent screen and said beam shield member.
